LAMP ATTACHING CLAMP

Le Roy O. Brown, Chicago, Ill., assignor to Justrite Manufacturing Company, Chicago, Ill., a corporation of Illinois

Application April 5, 1933, Serial No. 664,485

2 Claims. (Cl. 240—60)

The lamp of the type to which the invention relates is used by miners. Said lamps are mounted on lamp supporting devices secured to caps worn by these men. The lamps are provided with suspension hooks and engage ordinarily in a perforation in the top of the lamp-carrying device of the cap. In some instances the last mentioned device is equipped with a socket to receive the nose portion of the suspension hook of the lamp and serves to hold the latter against swinging relatively to said device, but in instances where said socket is not employed, the lamp is provided with a flexible cross-bar below the hook which is equipped with ogee curved end portions which are sprung over the side edges of the vertical portion of the lamp-carrying device of the cap for holding the lamp firmly in position on said device, in cooperation with the suspension hook.

In instances where the miner who purchases the lamp wears a cap equipped with the lamp-carrying device, having the aforesaid socket, he usually breaks off the last-mentioned cross-bar, which is soldered to the rear wall of the water chamber of the lamp, and in so doing, it happens quite frequently that the said wall of the water chamber becomes perforated and leaky.

The object of the present invention is to provide a detachable, flexible clamping device for the lamp, which is mounted thereon at the factory and shipped to the dealer with the lamp; the purpose being to make it easy for the miner to detach the clamp in the event that the cap worn by him is equipped with the last-mentioned socket to receive the nose of the suspension hook of the lamp. The advantage of this detachable clamp lies in the fact that it may be removed without distorting or perforating the wall of the water chamber of the lamp to which the cross-bar aforesaid has heretofore been soldered.

Heretofore, the said cross-bar has been made of a flat strip of spring brass and in soldering said strip to the wall of the water chamber of the lamp, the portion of said strip heated by the soldering iron lost its temper and became weak, so that in many instances one end portion of said cross-bar was broken away in the ordinary use of the lamp. The detachable clamp of the present invention is made of ordinary hard brass wire which is not only cheap, but also is stronger than the flat strip of metal heretofore used and accordingly, the clamp of the present invention is far more durable and efficient than the said cross-bars heretofore employed.

The main objects of the invention will be read-

ily understood and appreciated from the foregoing explanation.

A suitable embodiment of the invention is shown in the accompanying drawing wherein:

Fig. 1 is a side elevation of a miner's acetylene lamp, having a cylindrical water chamber horizontally disposed and which is equipped with a detachable clamp constructed in accordance with the invention; said lamp being shown as mounted upon a miner's cap, shown in fragment.

Fig. 2 is a fragmentary plan section on the line 2—2 of Fig. 1.

Fig. 3 is a top plan view of the structure, shown in Figs. 1 and 2.

Fig. 4 is a rear elevation of the lamp shown in Figs. 1, 2, and 3, showing the clamp of this invention in elevation.

Fig. 5 is a detail plan section on an enlarged scale on the line 5—5 of Fig. 4.

Fig. 6 is a side elevation similar to Fig. 1, showing the clamp of the present invention mounted upon a miner's acetylene lamp, wherein the cylindrical water chamber is vertically disposed.

In said drawing, the water tank (1) of the lamp is shown as equipped on its rear wall with a flat sheet metal plate (2) provided adjacent its lower end with a pair of side flanges (3) bent inwardly toward each other to provide a pair of opposed recesses along the side edges of said plate (2), said flanges (3) being provided along their free edges with outwardly projecting lips (4), the mouths of said opposed recesses being slightly narrower than the inner portions of said recesses.

The suspension hook (5) of the lamp is composed of wire which is suitably secured to the upper end portion of the strip (2) and is adapted to engage in a perforation in the upper portion of flange (6) of the lamp-carrying device of the miner's cap (7). The said device is composed of flat sheet metal and is of a width shown in Fig. 2, substantially equal to the largest lateral dimension of the lamp.

By reference to Figs. 1 and 6, it will be noted that the other end of the hook (5) is spaced from the water tank (1) of the lamp and thus provides a recess (8) in which the middle portion (9) of the clamp of this invention is adapted to be received.

The said clamp comprises a single piece of wire having a U-shaped middle portion comprising said portion (9) and a pair of arms (10), the terminal portion (11) of which extends laterally outwardly as shown in Figs. 2 and 4 and are pro-

vided at their extremities with substantially ogee curved projections (12).

The said arms (10) of said clamp normally diverge from each other and are contracted to the 5 position shown in Fig. 4 when engaged in the recesses formed by the flanges (3) of the plate (2). In mounting said clamp on the lamp, the portion (9) is first passed into the recess (8) and the arms (10) are then forced toward each other so 10 that their lower end portions may pass between the said flanges (3) of the plate (2). When so disposed said arms (10) are forcibly spread apart and these spring into the recesses formed by the flanges (3) and said clamp is then mounted rigidly upon the lamp.

In mounting the lamp on the supporting device of the miner's cap (7), the terminal portion (12) of the clamp may be first sprung over the side edges of the device (6) at a point sufficiently 20 high to bring the terminal of the hook (5) above and in alignment with the perforation into which it is to be passed, and the lamp then moved downwardly relatively to the device (6) until it has obtained the position shown in Figs. 1 and 6 or, 25 the hook may be first inserted into said perforation and the terminal portion or projection (12) then sprung over the side edges of the device (6).

Obviously, the said clamp is easily detached from the lamp in the event that it is not required.

30 The structure shown in Fig. 6 does not differ from that shown in Figs. 1 to 5, inclusive, except as to the shape of the water tank (13) of the lamp.

35 I claim as my invention:—

1. Means for detachably securing a miner's lamp, equipped with a suspension hook to a conventional miner's cap equipped with a flat front plate and a perforation arranged at the top of 40 said plate to receive the said suspension hook, comprising a pair of opposed socket members

mounted upon the back of the lamp body below said hook, and a flexible metal member comprising an inverted U-shaped middle portion suspended from a portion of said suspension hook, and having the lower end portions thereof engaged in the said socket formations whereby said member is engaged at three points with the lamp, and divergent arms at the lower end of said middle portion equipped with terminal flexible projections adapted to be sprung over and into engagement with the side edges of the said plate, said projections cooperating with said hook to provide a three-point engagement of the lamp with said plate to hold the lamp firmly engaged with the cap.

2. Means for detachably securing a miner's lamp equipped with a suspension hook to a conventional miner's cap equipped with a flat front plate and a perforation arranged at the top of 80 said plate to receive the said suspension hook,

comprising a pair of opposed socket members mounted upon the back of the lamp body below said hook, and a flexible metal member comprising an inverted U-shaped middle portion suspended from a portion of said suspension hook,

and having the lower end portions thereof engaged in the said socket formations whereby said member is engaged at three points with the lamp, and divergent arms at the lower end of said middle portion equipped with terminal flexible projections adapted to be sprung over and into engagement with the side edges of the said plate,

said projections cooperating with said hook to provide a three-point engagement of the lamp with said plate to hold the lamp firmly engaged 90 with the cap,

comprising a pair of opposed socket members mounted upon the back of the lamp body below said hook, and a flexible metal member comprising an inverted U-shaped middle portion suspended from a portion of said suspension hook,

and having the lower end portions thereof engaged in the said socket formations whereby said member is engaged at three points with the lamp, and divergent arms at the lower end of said middle portion equipped with terminal flexible projections adapted to be sprung over and into engagement with the side edges of the said plate,

said projections cooperating with said hook to provide a three-point engagement of the lamp with said plate to hold the lamp firmly engaged 100 with the cap,

comprising a pair of opposed socket members mounted upon the back of the lamp body below said hook, and a flexible metal member comprising an inverted U-shaped middle portion suspended from a portion of said suspension hook,

and having the lower end portions thereof engaged in the said socket formations whereby said member is engaged at three points with the lamp, and divergent arms at the lower end of said middle portion equipped with terminal flexible projections adapted to be sprung over and into engagement with the side edges of the said plate,

said projections cooperating with said hook to provide a three-point engagement of the lamp with said plate to hold the lamp firmly engaged 110 with the cap,

comprising a pair of opposed socket members mounted upon the back of the lamp body below said hook, and a flexible metal member comprising an inverted U-shaped middle portion suspended from a portion of said suspension hook,

and having the lower end portions thereof engaged in the said socket formations whereby said member is engaged at three points with the lamp, and divergent arms at the lower end of said middle portion equipped with terminal flexible projections adapted to be sprung over and into engagement with the side edges of the said plate,

said projections cooperating with said hook to provide a three-point engagement of the lamp with said plate to hold the lamp firmly engaged 115 with the cap,

LE ROY O. BROWN.
